FOLDING-MACHINE.

1,281,555.

Specification of Letters Patent. Patented Oct. 15, 1918.

Application filed September 20, 1913. Serial No. 790,892.

To all whom it may concern:

Be it known that I, PERLEY R. GLASS, a citizen of the United States, residing at Brookline, in the county of Norfolk and State of Massachusetts, have invented certain Improvements in Folding-Machines, of which the following description, in connection with the accompanying drawings, is a specification, like reference characters on the drawings indicating like parts in the several figures.

This invention relates to improvements in machines for folding the edges of sheet material and is herein illustrated in a machine intended for folding the edges of parts of boots and shoes. In work of this kind parts are often encountered having edges of short curvature, and heretofore this work has been handled with much difficulty by folding machines. One object of the present invention is to provide a machine whereby this class of work may be easily folded.

In my prior application Serial No. 725, 381, which matured into Patent No. 1,270, 25 753 on June 25, 1918, I have described a folding machine having mechanism constructed and arranged to plait the folded over margin when a convexly curved edge of the work is encountered. I have found, 30 however, that the plaits formed by said mechanism are not invariably uniform in size with the result that the convex curve of the folded edge does not always correspond, as it should, to the curve of the edge before it 35 was folded. Thus, instead of the smooth curve which the folded edge should present a slightly uneven edge caused by irregular plaiting is occasionally produced.

An important feature of the present invention consists in the provision of means 40 for plaiting the edge turned back so that the excess material will be distributed uniformly throughout the extent of the curve. In one of its aspects, accordingly, the present invention consists in the provision of a 45 folding machine having improved means for plaiting the folded edge of sheet material.

Another important feature of the invention consists in mounting all the instrumentalities which act upon the material in such a manner as to leave the work table free and unobstructed at all points except where the work is being actually operated upon. This

permits work of various irregular shapes to be swung into all desired positions so that 55 the edge being folded may be presented in the most favorable manner to the instrumentalities of the machine.

In folding sheet material it is of great importance that the edge shall not be stretched 60 in the process as otherwise the finished work will assume a wavy character. In this connection an important feature of the present invention consists in supporting in an inclined manner that portion of the material 65 adjacent to the point at which the folding instrumentalities are operating. By this expedient the rearmost point on the margin of the folded edge and the foremost point on the margin of the unfolded edge relatively 70 to the direction of feed are brought closer together than if the work were supported flatly and so the tendency to stretching of the material between these two points is eliminated and the formation of plaits 75 facilitated.

These and other features of the invention will be best understood and appreciated from the following description of a preferred embodiment thereof, selected for purposes of illustration and shown in the accompanying drawings, in which:

Fig. 1 is a view of the machine in side elevation;

Fig. 2 is a view in perspective of the 85 mechanism for actuating the snipping knife and mechanism for actuating the work support, together with their associated parts;

Fig. 3 is a view in front elevation of the 90 folding instrumentalities;

Fig. 4 is a view in perspective showing one side of the hammer;

Fig. 5 is a view in perspective showing the folder and its actuating mechanism;

Figs. 6 and 7 illustrate the hammer and 95 its actuating mechanism, Fig. 6 showing also part of the feeding mechanism;

Figs. 8 to 11 are views in perspective showing the folding instrumentalities in the different positions which they occupy, and 100

Figs. 12 and 13 are detail views showing the relation of the feeding mechanism to the mechanism for rendering the snipping knife operative or inoperative.

The machine has a base 4 to which is piv- 105 oted a frame or casing 2 having cast there-

in bearings for the main driving shaft 6. The shaft 6 carries at one end a belt pulley 8 by which the machine is driven, and a clutch lever 10 is pivoted to the base 4 and arranged to control the operation of the machine through a treadle, not shown. To the upper part of the casing 2 is secured a work table 12 having a rearwardly projecting portion from which extends an overhanging arm 13. The various instrumentalities of the machine are mounted upon the extreme end of the overhanging arm 13 or beneath the work table at a point opposite the end of the arm.

15 The work is directed to the folding instrumentalities by a plow 30 adjustably secured in a slot in the work table 12. The plow has a vertical slot in its upper edge to receive the end of a pivoted gage 32 which 20 determines the width of the folded margin by engaging the partially upturned edge of the material as it is fed past the plow. The gage 32 is pivoted on a stud 34 set in a block 35 adjustably secured to a vertical bar 36 which, in turn, is adjustably fitted in the end of the arm 13. It will be understood 25 that the plow 30 lifts the margin of the work slightly and presents it in this condition to the movable folding instrumentalities. The width of the folded margin is determined by the relative adjustment and shape of the plow 30 and gage 32. It is intended to supply plows in assorted heights so that when any considerable variation in 30 the width of the margin is desired a higher or lower plow may be substituted. For the purpose of effecting minor variations in this respect there is provided an adjusting screw 37 which passes through the rear side of 35 the block 35 and bears against a lateral projection 38 on the bottom of the gage 32 as shown in Fig. 8. By turning this screw into the block 35 the gaging end of the member 32 is held in a more elevated position. A 40 leaf spring 39 is secured to the block 35 and arranged to hold the operative end of the gage down and consequently to hold the projection 38 against the lower end of the screw 37.

50 It has been stated that the block 35 is adjustably secured to the bar 36. To this end the bar 36 is provided with a horizontally extending slot through which extends a clamping screw (see Fig. 8) into 55 block 35. One purpose of this adjustment is to provide still further opportunity for adjusting the gage 32. It will be seen, therefore, that the position of the gage 32 may be adjusted by four independent means; 60 first by changing the height of the plow 30; second, by turning the screw 37; third, by moving the block 35, and fourth, by moving the bar 36 and so varying the vertical position of the fulcrum stud 34. By reason 65 of these provisions for adjustment it is pos-

sible to position the gage to a nicety and so adapt the machine for operating on material of all different varieties.

The rear edge of the plow 30, relatively to the direction of the feed, is shaped to cooperate with the snipping knife when it is desired to slit the margin of the work. The snipping knife 40 is adjustably secured in the lower end of a bent lever 42 pivotally mounted on a stud 44 projecting from the 75 end of the arm 13 at a point behind the bar 36. The snipping knife is oscillated about the stud 44 by a bent link 46 pivotally connected to the lever 42 near its elbow and connected at its lower end to one arm of a lever 80 48. The lever 48 is mounted for pivotal movement about a journal stud 50 extending at right angles to the driving shaft 6. The lever 48 is fast to a sleeve 52 to which is also secured a bell crank lever 54 one end 85 of which carries a ball 56 which projects into a yoke 58. The yoke 58 is formed as part of a bar 60 which is arranged for vertical reciprocation in the machine frame and is actuated by an eccentric 62 fast on the 90 forward end of the shaft 6. The ball end 56 of the lever 54 is disposed between two cup members the upper of which is rigidly set in the yoke 58 and the lower of which, that designated by reference character 64, is 95 loosely mounted in the lower side of the yoke. When the member 64 occupies its lowest position there is sufficient lost motion between it and the ball end 56 to permit the snipping knife to remain at rest, 100 and under these circumstances the snipping knife occupies the position shown in Fig. 1, that is, a position remote from the work.

When it is desired to snip the edge of the work the cup member 64 is moved upwardly 105 into engagement with the ball end 56 of the lever 54 and locked in this position so that thereafter the lever 54 will be oscillated as the yoke is reciprocated. To this end the bar 60 is provided with a transverse guideway 110 for a sliding cam bar 68 on the upper edge of which rides the member 64. The cam bar 68 is pivotally connected at its rear end relatively to the direction of feed to a bell crank lever 70 to which is also connected a treadle 115 rod 72 by which the position of the cam bar may be shifted and the snipping knife rendered operative or inoperative at will.

The cam bar is connected to the lever 70 by a short shaft journaled in a boss on said lever and carrying at one end a disk 74 and at the other end a projecting arm 76. A spring locking pin 78 is mounted in the disk 74 and arranged to fit into one of two holes formed in a disk 71 rigidly secured to the 125 end of the lever 70. By causing the pin 78 to enter one or the other of these holes the arm 76 may be locked in one of two positions, that is, in a substantially horizontal position as shown in Fig. 13, or in a substantially 130

vertical position as shown in Fig. 12. In the latter position the arm 76 engages a roller 77 on a part of the feeding mechanism for a purpose which will be hereinafter set forth.

As has been explained, the snipping knife 40 coöperates with a stationary shear blade formed by one end of the plow 30. It is desirable to employ light knife actuating mechanism on account of the high speed at which the machine is run and in order that there may be no danger of the movable knife being crowded away from the stationary blade by a thick or tough piece of work a bearing is provided to back up the arm of the knife carrying lever 42. This bearing comprises a stud 41 carried by the bar 36 and having a threaded shank which enters a threaded socket in the end of an adjusting stud 43 by which the position of the bearing stud 41 may be adjusted.

In the rear of the snipping knife, relatively to the direction of feed, is disposed the folder 80. This member, as shown in Fig. 5, is guided for reciprocation in an oblique path in guideways formed in the machine frame. It comprises a straight bar terminating in a finger with its end beveled on one side. It is connected through links 81, 82 and 83 to the end of an oscillating cam lever 84. The lever 84 is pivotally mounted upon a shaft 9 located at one side of the machine frame in parallel relation with the main shaft 6 and is oscillated by an eccentric 16 fast to that shaft.

The folder 80 coöperates, in partially forming the fold, with a yieldingly mounted creaser 90 carried by the bar 36 at the end of the arm 13. The shank of the creaser is 40 slidingly received in a vertical bore formed in the block 92 pivotally secured to the bar 36. A finger lever 94 is pivoted for movement about the axis of the block 92 and arranged to engage the shank of the creaser whereby the latter may be raised from the work if desired in a manner similar to that shown in British Patent No. 15,405 of 1912. In order to permit an unobstructed view of the portion of the work being operated upon 50 the creaser is formed with a goose neck portion which is provided at its lower end with a portion offset laterally and a creasing portion which is disposed opposite to the folder 80. At its rear edge, relatively to the direction of feed, the creaser is so shaped that the hammer which will be presently described may act in close proximity to it.

The work beneath the creaser rests upon a supporting block 100 having a lateral projection 101 as shown in Fig. 2 and a slot to receive a portion projecting from the anvil 104 which will be presently described. The supporting block 100 is formed on the end of a lever 106 having the handle 107 and being 65 pivoted for movement about a journal shaft

108. Beside the lever 106 and fastened to the rock shaft 108 by a screw 110 is a second lever 109.

The block 100 is intermittently depressed in order to relieve the work and to permit 70 the feeding movement to take place by an arm 112 which is secured to the shaft 108 and connected through a link 114 to the upper fork of a cam lever 116 which, similarly to the cam lever 84, is pivotally mounted 75 upon the shaft 9 and oscillated by an eccentric 14 on the shaft 6. The lever 106 has two lateral projections located on opposite sides of the shaft 108, beneath one of which is located an extension of the hub of 80 the lever 109 and beneath the other of which is located a spring plunger 103 carried by said lever 109. Consequently when the shaft 108 is rocked the lever 106 is rocked to raise and lower the support 100, while at any time 85 said support may be depressed by lifting the handle 107.

To the rear of the supporting block 100, relatively to the direction of feed, is located the anvil block 104 upon which the fold is 90 pressed and completed by the hammer as will hereinafter appear. The work supporting surface of the anvil 104 is beveled obliquely toward the rear or back of the machine (the right-hand end as viewed in 95 Fig. 1) and toward the supporting block 100. This construction of the anvil constitutes an important feature of the invention and contributes greatly to improve the operation of the machine by eliminating all tendency to stretch the work in the folding and plaiting operation. The anvil coöperates with the hammer in feeding the work.

It has been found that in folding sheet material on a flat bed, owing to the fact that 105 the foremost portion of the unfolded margin relatively to the direction of feed is held upright and the rearmost portion of the folded margin is held flat upon the bed, an objectionable tension is exerted on the work 110 between those two points. The effect of providing the anvil with an inclined surface which coöperates with an inclined surface on the hammer is to relieve this tension and prevent stretching. This relieving of the 115 tension is advantageous not only on straight work but also on convexly curved work where the margin is to be plaited. The inclined surface of the anvil also facilitates the formation of the transverse creases of 120 the plaits.

The construction which has proved most advantageous in eliminating the objectionable stretching of the work is that in which the face of the anvil is obliquely inclined, or 125 beveled obliquely, that is, inclined in two directions. In this case, its face is inclined downwardly toward the rear and also toward the right.

Slidably mounted in ways formed in the 130

machine frame, beneath the table 12, is a slide carrier 120 in which is mounted a journal shaft 122. The hammer 150 is mounted for oscillation about the shaft 122 and is also carried bodily transversely thereby in the feeding operation. The anvil block 104 is secured to the upper face of the slide carrier 120 beneath the hammer 150. The hammer 150 is oscillated through an actuator 152 pivotally mounted upon the shaft 122 and having projections extending on either side of the part of the hammer that extends below the shaft 122. In this portion of the hammer there is provided a spring plunger 153 which bears against one arm of the actuator and holds the lower portion of the hammer back against a stop screw 154 set in the other arm of the actuator. This construction affords a yielding connection between the hammer and the actuator and as the hammer is operated through the actuator it will be seen that its engagement with the work is of a yielding character and that it will be permitted to yield against the compression of the plunger 153 when an excessively thick portion in the work is encountered. The actuator 152 has a forwardly projecting arm to which is pivoted a short link 156. This is connected through the links 157 and 158 to the upper fork of the cam lever 160 pivotally mounted on the shaft 9 and oscillated by an eccentric 18 on the shaft 6.

Transverse reciprocation of the slide carrier 120 together with the hammer 150 and anvil 104 is secured in the following manner. At its rear end relatively to the direction of feed the slide 120 has a pair of downwardly projecting ears 162 between which is received a block 164. The latter is pivotally secured to the vertical arm of a bell crank lever 166 pivotally mounted on a stud 168 set in the machine frame and connected at its other end to a substantially vertical link 170. The link 170 is connected to a block 172 slidably received in a curved slot formed in the body of a cam lever 174 pivotally mounted on the shaft 9. The cam lever 174 is oscillated by an eccentric 20 on the shaft 6. The extent of transverse reciprocation imparted to the slide carrier 120 is determined by the position of the block 172 with respect to the axis of the cam lever 174. In other words, when the block 172 is moved toward the shaft 9 a shorter vibration is imparted to the bell crank lever 166 and a correspondingly shorter reciprocation to the slide carrier 120 and the feeding members 104 and 150. The block 172 is extended beyond the cam lever 174 and is engaged by the forks of a feed regulating lever 176 as shown in Fig. 12. This lever at its outer end extends through the casing, as shown in Fig. 1, and may be set in any adjusted position by the operator. As shown, it occupies a position

of predetermined maximum feed determined by a pin 177. The position of the lever for minimum feed is determined by an adjustable stop screw 178 threaded into a bracket secured to the machine frame above the end 70 of the feed lever.

The hammer 150 is provided in its upper surface with a slot in which is received a foot 180, herein shown as formed of spring sheet steel. The foot projects slightly beyond the end of the hammer and then transversely to a point above the lateral projection 101 on the anvil block 104. At its extreme end the foot 180 is turned downwardly so that it will be the first part of the hammer to engage the work. On account of its shape the end of the foot engages the work at a point substantially in line with and outside the creaser and folder. Consequently, as soon as the work has been moved into position to have the first fold made in it the end of the foot 180 will engage the work and start the feeding operation, whereas formerly it was necessary to advance the work by hand beneath the hammer proper.

On its lower side the hammer is provided with a groove 181 which is slightly oblique but substantially transverse to the line of feed, as shown in Fig. 4, said groove being located in that portion of the operative face 95 of the hammer which is nearer the folder. The purpose of this groove is to insure that the work shall be evenly plaited when convexly curved portions of it are being folded. In plaiting the work there is, in addition to the usual fold, a series of plaits which extend at an angle to the direction of the fold, such a plait in the process of formation being shown at 200 in Fig. 10. When, therefore, a hammer having a groove such as that shown in Fig. 4 is moved downwardly, since a space is formed for the reception of the plait, said plait is crowded into said groove, instead of being pushed back as was sometimes formerly the case, into the unfolded portion. The plaits are then laid uniformly one over another in a forward direction.

With the parts in the position shown in Fig. 10 the work is held down by the toe of the creaser 90 only and can therefore be turned about a sharp curve as in the machine of my prior application. As shown, several plaits have been made and a loop or pucker has been raised beneath that portion of the hammer in which the groove 181 (see Fig. 4) is formed. Consequently, when the hammer descends the loop is received in this groove and standardized, so to speak, as to size. The hammer does not at this time press this loop to form a plait but grips the material on both sides of it, at the same time pressing down a previously formed loop, and then in the feeding movement carries this loop along into position to be pressed upon the next succeeding descent of the hammer. In this

way the size of the plaits is maintained substantially uniform.

The purpose of the arm 76 will be apparent from the foregoing description. When 5 this arm is locked in its vertical position, as shown in Fig. 12, it engages with a roller 77 mounted on the outer end of the block 172. Consequently when the treadle rod 72 is depressed in order to throw the snipping 10 knife out of operation the block 172 is shifted away from the axis of the shaft 9 and the feeding movement of the machine is correspondingly increased. And con- 15 versely, if the feed controlling lever is ma- nipulated to decrease the rate of feed, the knife is thrown into operation. As has been explained, in the illustrative machine the feed mechanism is normally in position to produce the maximum feed and the knife is 20 normally in inoperative position. However, if it is desired to throw the snipping knife into or out of operation independently of the feeding mechanism the disk 74 is turned so as to lock the arm 76 in its horizontal position 25 as shown in Fig. 13 where it is entirely out of range of the roller 77.

In operating the machine the supporting block 100 will be depressed by the handle 107 and the work inserted until its edge comes 30 opposite to the folder 80 and the creaser 90, the hammer 150 with the foot 180 being raised above the work. When the machine is set in operation through the clutch lever 10 the folder rises turning a portion of the 35 margin over the edge of the creaser. The operative end of the foot 180 is located a sufficient distance in front of the creaser so as not to interfere with this operation, but in its subsequent downward movement the 40 foot 180 engages the body portion of the work and advances it in its subsequent transverse movement. This arrangement of the foot is advantageous because it insures a prompt feeding movement of the work. 45 Otherwise the operator would be obliged to advance the work past the folder and creaser and into the range of the body of the hammer before any feeding movement would take place. The first oscillation of 50 the hammer merely completes the fold by pressing the upturned portion of the margin down upon the body portion of the material. As the work progresses along a curved edge the material is swung slightly with respect 55 to the folding instrumentalities and the ensuing operations serve to plait the upturned portion of the edge in the manner suggested by Fig. 10 of the drawings. From this figure it will be seen that the combined effect 60 of the inclined anvil block with the creaser and folder is to form a slight loop between the upturned portions of the margin and the part in which the fold is completed. When, therefore, the hammer descends, the groove in 65 said hammer receives this loop or bight,

grips the material on both sides of said loop and feeds the loop forward upon the inclined bed, so that upon the next descent of the hammer this previously fed loop will be pressed down to form a bight; and this 70 pressing down, by reason of the inclined faces of the anvil and hammer, is caused to take place in a forward direction relatively to the direction of feed so that each bight is laid properly to overlap the previous one. 75

Having thus described my invention, I claim as new and desire to secure by Letters Patent:

1. A machine of the class described, having, in combination, a support over which 80 sheet material is fed, means for folding the margin of the material over upon the body portion thereof, means for forming a succession of loops in the folded over margin, and means for pressing a loop down into place 85 upon the body portion of the material and at the same time preventing a subsequently formed loop from being straightened out.

2. A machine for folding the edges of sheet material having, in combination, a hammer 90 for pressing the fold, loop-forming means, and an inclined support for a portion of the edge adjacent to the loop formed by said means, said support being located to co-operate with the hammer in pressing the 95 fold.

3. A machine of the class described, having, in combination, a support over which the work is fed, and feeding, folding and fold-pressing means including a hammer and 100 an anvil constructed and arranged to press the fold in a position at an angle to the body portion of the work.

4. A machine of the class described, having, in combination a support over which 105 sheet material is fed, means for turning up the margin preparatory to pressing it down upon the body portion of the material and for forming a loop in the turned up margin when a convexly curved margin is encountered, and a pressing member shaped to preserve a given loop while the previously formed loop is being pressed into a bight. 110

5. A machine for folding the edges of sheet material having, in combination, loop-forming means, and a hammer movable transversely to the edge of the work and then longitudinally thereof, first to standardize the loop and then to feed the work, said hammer having an obliquely disposed groove 115 in its work engaging face.

6. A machine for folding the edges of sheet material having, in combination, edge turning and loop-forming means, a hammer, and an anvil having its face disposed 125 obliquely to the body portion of the work.

7. A machine for folding the edges of sheet material having, in combination, work-feeding, edge-turning and fold-pressing devices including a hammer and arranged to 130

press the completed fold in a position oblique to the body portion of the work.

8. A machine for folding the margin of sheet material having, in combination, means for progressively turning up the margin of a piece of material, and means for pressing said turned up margin down upon the body of the material, said last named means including an anvil having a supporting face inclined obliquely toward the means for turning up the margin.

9. A machine for folding the margin of sheet material having, in combination, means for progressively turning up the margin of a piece of material, and means for pressing said turned up margin down upon the body of the material, said last named means including an anvil having a supporting face inclined obliquely toward the means for turning up the margin, and a hammer having a complementally inclined co-operating face.

10. A machine of the class described, having, in combination, a work table, means for turning up the margin of the work, an anvil having a face inclined upwardly from the table and adapted to support a portion of the body of the work, and means for pressing the upwardly turned margin down upon that portion of the work which is supported by the inclined face of the anvil.

11. A machine for folding the margin of sheet material having, in combination, co-operating devices for forming a loop in the margin of the material, and a hammer and anvil for feeding the material and pressing the fold, one of said last named members being provided with a depression to receive the loops successively during the feeding operation.

12. A machine for folding the margin of sheet material having, in combination, a creaser, and feeding, folding and pressing mechanism including a folder for up-turning portions of the edge about the creaser, and a hammer having a projection arranged to act on the material at a point in the rear of the creaser relatively to the edge of the material.

13. A machine for folding the margin of sheet material having, in combination, a creaser held from movement in the line of feed, a folder for turning up the margin of the material about the edge of the creaser, a hammer for pressing the upturned margin down upon the body of the material, and a feed member arranged to contact with the material at a point inside the folded margin and substantially in line with the operative portions of the folder and the creaser.

14. A machine of the class described having mechanism for slitting, mechanism for folding, and mechanism for feeding a piece of material, in combination with means for connecting the slitting mechanism with the feeding mechanism in such manner that they may be controlled together and for discon-

necting the two mechanisms in such manner that they may be controlled separately.

15. A machine of the class described having mechanism for slitting, mechanism for folding, and mechanism for feeding a piece of material, in combination with a member adjustable into one position to connect the feeding mechanism with the slitting mechanism and into another position to render said last two mechanisms independent. 75

16. A machine for progressively folding the margin of sheet material having, in combination, slitting mechanism, folding mechanism, and feeding mechanism, a treadle movement of which varies the rate of actuation of the feeding mechanism, and a member movable into one position to connect said treadle with the slitting mechanism and into another position to disconnect it therefrom whereby the slitting of the material 80 can be made dependent upon or independent of the feeding mechanism as desired.

17. A machine of the class described, having, in combination, means for feeding a piece of material and for slitting and folding the margin thereof, means for varying the rate of feed, and means operating when the rate of feed is decreased to render the slitting means operative. 90

18. A machine of the class described, having, in combination, feed mechanism normally operative to produce a given speed movement, slitting mechanism normally inoperative, means for decreasing the rate of feed, and connections between the feed 100 mechanism and the slitting mechanism such that decreasing the rate of feed renders the slitting mechanism operative. 95

19. A machine of the class described, having, in combination, means for feeding a piece of material, means for slitting and folding the margin thereof, means for varying the rate of feed, and means for connecting the slitting means with the feed varying means and for disconnecting it therefrom. 105

20. A machine for folding the margin of sheet material having, in combination, a work table, an overhanging arm, folding devices mounted upon said table and arm at opposite points, means for feeding the work 115 over the table, a snipping knife movably mounted on the arm near the end thereof, and an actuating connection therefor passing through the table.

21. A machine for folding the margin of sheet material having, in combination, a work table, an overhanging arm, a creaser carried thereby, a snipping knife movably mounted on the arm near the end thereof and adjacent to the creaser, actuating mechanism therefor beneath the table, connections extending substantially vertically through the table, and means for feeding the work over the table. 120

22. A machine for folding the margin of 130

sheet material having, in combination, means for supporting a piece of sheet material, a creaser for determining the fold line, and a folding member arranged to reciprocate in a path adjacent to the creaser to turn the work over the edge of the creaser, said member having an end beveled on the side facing the folded portion of the edge.

23. A machine for folding the margin of sheet material having, in combination, a work table having an overhanging arm, a slide adjustably secured in position at the end of the arm, a pivoted gage carried thereby, and a gage supporting member secured 15 to the table.

24. A folding mechanism comprising means for guiding, feeding and turning the edge of a flexible material; including an approximately horizontal work plate to support the material; a fold-presser block; and a fold-presser device for pressing the fold of the material upon its body part, the faces of said block and fold-presser being positioned 20 at an angle to the work-supporting plate when in operating position.

25. A folding mechanism comprising means for guiding, feeding, turning and pressing the edge of a flexible material, including a work-supporting plate and co-acting fold-presser members having fold-presser surfaces positioned at an angle to the work-supporting plate.

26. A folding mechanism comprising means for guiding, slitting and turning the edge 35 of a flexible material combined with a work-supporting plate and members having feeding and fold-pressing surfaces positioned at an angle to the work-supporting plate.

27. A folding mechanism comprising means for guiding, feeding and turning the edge 40 of a flexible material, including a work-supporting plate; and members having fold-presser surfaces positioned at an angle to the work-supporting plate, one of said members being movable, the movable fold-presser surface having a slot in its face.

28. A folding mechanism comprising means for guiding, feeding and turning the edge of a flexible material; including an approximately horizontal work-plate to support the material; a fold-presser block; and a movable fold-presser device having a slot in its fold-presser surface for pressing the fold of the material upon its body part, the pressing 50 faces of the block and device both being positioned at an angle to the work-supporting plate when in operating position.

29. A machine for folding the margin of sheet material, having, in combination, 60 means for progressively turning up the margin of a piece of material, and means for pressing said turned up margin down upon the body of the material, said last-named means including an anvil having an inclined 65 supporting face.

30. A machine for folding the edges of sheet material having, in combination, edge folding means, means for forming a loop in a portion of the edge of the work and pressing it down on the body portion of the work 70 in the form of a plait, and a support having a surface shaped to bend a portion of the folded edge adjacent to the loop transversely to the plane of the body of the work.

31. A machine for folding the margin of sheet material having, in combination, means for progressively turning up the margin of a piece of material, and means for pressing said turned up margin down upon the body of the material, said last-named 80 means including an anvil having a supporting face inclined toward the rear of the machine.

32. A folding mechanism comprising an approximately horizontal work-plate, and 85 means for feeding, guiding and turning the edge of flexible material including a fold-presser block and a fold-presser device for pressing the fold of the material upon its body part, the faces of which are both positioned 90 at an angle to the work-supporting plate when in operating position.

33. A folding mechanism comprising means for guiding, feeding and turning the edge of a flexible material including a work-supporting plate and co-acting fold-presser members having fold-presser surfaces positioned at an angle to the work-supporting plate.

34. A machine for folding the margin of sheet material, having, in combination, means for progressively turning up the margin of a piece of material, and means for pressing said turned up margin down upon the body of the material, said last-named means including an anvil having a supporting face inclined toward said first-named means.

35. A machine of the class described, having, in combination, feed mechanism, normally operative to produce a given feed movement but capable of being controlled to produce a different movement, slitting mechanism, folding mechanism, means for rendering the slitting mechanism operative or inoperative at will, and connections between the slitting mechanism and the feed mechanism such that rendering the slitting mechanism inoperative increases the rate of feed.

36. A machine for folding the margin of sheet material over upon the body portion thereof having, in combination, means for feeding the material and a folder and a hammer past which the material is fed, said hammer having in its operative face a groove 125 extending substantially transverse to the line of feed.

37. A machine for folding the margin of sheet material over upon the body portion thereof having, in combination, means for 130

feeding the material and a folder and a hammer past which the material is fed, said hammer having cut in that portion of its operative face which is nearer the folder a groove extending substantially transverse to the line of feed.

In testimony whereof I have signed my

name to this specification in the presence of two subscribing witnesses.

PERLEY R. GLASS.

Witnesses:

FRED W. GUIBORD,
NORMAN C. HUSSEY.
